L. W. V. WILMS.
PLANTAR ARCH AND METATARSAL FOOT SUPPORT.
APPLICATION FILED JUNE 30, 1919.

UNITED STATES PATENT OFFICE.

LEE W. V. WILMS, OF CHICAGO, ILLINOIS.

PLANTAR-ARCH AND METATARSAL FOOT-SUPPORT.

1,375,340.

Specification of Letters Patent. Patented Apr. 19, 1921.

Application filed June 30, 1919. Serial No. 307,702.

To all whom it may concern:

Be it known that I, LEE W. V. WILMS, a citizen of the United States, residing at Chicago, in the county of Cook and State 5 of Illinois, have invented certain new and useful Improvements in Plantar-Arches and Metatarsal Foot-Supports, of which the following is a specification.

This invention relates to a device of the 10 kind worn in shoes for the support of the foot for strengthening certain parts and for correcting distorted and weakened conditions of particular portions or members thereof.

15 The principal or main object of the invention is to provide a support to rest and strengthen the plantar muscles and to support and correct the weakened and distorted conditions of the metatarsal arch of the 20 human foot. Another object of the invention is to furnish a support of the above mentioned character, the parts of which shall be so constructed and operatively arranged as to permit of the same being of 25 sufficient length to afford yielding or flexible transverse support to the foot anteriorly just back of the heads of the metatarsal bones without causing the downward and pulling away movement of the rear portion 30 of the plantar supporting plate in the heel of the shoe when the user steps on the ball of the foot and throws weight over on the toes in walking.

Still another object is to provide a support which shall have a plurality of separately acting and yieldingly supported sections disposed in its front portion, the free front parts of which will afford distinct bearings on the insole of the shoe and thus 40 prevent them gouging or cutting into the same as is done by most metal arches heretofore in general use. A further object is to so mount sections of the device that they may be readily detached if desired. Other 45 objects and advantages of the invention will be disclosed in the following description and explanation.

In the accompanying drawing which serves to illustrate an embodiment of the invention,

50 Figure 1 is a plan view of the device.

Fig. 2 is a bottom or inverted plan view thereof.

Fig. 3 is a longitudinal sectional view

taken on line 3—3 of Fig. 2, looking in the 55 direction indicated by the arrows.

Fig. 4 is a cross sectional view of the plantar muscle supporting plate taken on line 4—4 of Fig. 3, looking in the direction indicated by the arrows.

60 Fig. 5 is a similar view thereof taken on line 5—5 of Fig. 4, looking in the direction indicated by the arrows, and

Fig. 6 is a bottom plan view showing a modification in the manner of securing the 65 sectional members of the device to the flexible supporting member.

Corresponding reference numerals indicate like parts throughout the different views of the drawing, in which it will be 70 understood that the device therein shown is for the left foot.

The device consists of an elongated member or plate 10, of leather or other suitable flexible material, which may be shaped to fit 75 or conform to the lines of a variety of sizes and shapes of shoes and feet, a long or plantar plate of metal 11, and a plurality of shell-shaped or upwardly dished metallic sections 12 and 13, mounted transversely on 80 the lower surface of the front portion of the member 10 above and extended forwardly beyond the front part of the plantar plate. The member or plate 10 serves the purpose of supporting the plantar or long 85 plate 11 and the upwardly dished or convexed sections or members 12 and 13, as well as, a comfortable support or rest for the foot when the device is located within a shoe on the insole thereof.

90 As shown in Figs. 2 and 3, the plantar plate 11 is secured near its inner rear portion, by means of a rivet 14, to the lower surface of the member or supporting plate 10 near its inner edge at or in the anterior heel 95 portion thereof and has a forwardly and outwardly extended marginal edge or end adapted to fit comfortably under the anterior portion of the heel of the foot. It will also be seen and understood by reference to said 100 figures of the drawing, that the plantar plate is of sufficient length to extend and transversely terminate at its front end at a point below the member 10, which when in place in the shoe will lie about one inch forwardly 105 under the long or metatarsal bones of the foot. The plate 11 is longitudinally arched from one of its ends to the other end there-

of, and has its posterior portion downwardly arched or concaved and its anterior portion convexed or transversely arched as is clearly shown in Figs. 4 and 5 of the drawing. Be-
5 sides being longitudinally arched, the plate
11 is by preference provided on its inner edge
with a slightly upturned flange 15 to rein-
force a similarly shaped flange or portion 16
on the inner edge of the member 10, which
10 latter the flange 15 underlies. The front
portion of the plate 11 is secured near its
inner edge by means of a rivet 17 to the
member 10, which rivet is located some dis-
tance rearwardly of the front end of the
15 plate 11, as is clearly shown in Figs. 1, 2,
and 3 of the drawing.

Mounted transversely on the lower surface
of the member 10 and secured thereto prefer-
ably by hollow rivets 18 is an upwardly
20 curved or dished metallic section 12, which
as shown has its rear portion located above
the front portion of the plate 11, and is ex-
tended at its front portion forwardly of said
plate. Transversely mounted on the lower
25 surface of the member 10 is another up-
wardly curved or dished metallic section 13,
the rear portion of which preferably over-
lies the front portions of both the section 12
and the plate 11, and is by preference se-
30 cured to the member 10 by means of hollow
rivets 18 as shown.

Thus it will be seen that the lower or free
front ends of the plate 11 and sections 12
and 13 are arranged to rest on the upper
35 surface of the insole of the shoe so as to
provide separate and distinct bearing sur-
faces or portions. As these sections are up-
wardly curved or dished or transversely
40 arched, and as before stated, as they are
yieldingly supported by the flexible member
10 at a point thereon just back of the heads
of the metatarsal bones when the device is
in use, they will give support to and
45 strengthen the weakened conditions of the
metatarsal arch of the foot.

In Fig. 6 of the drawing is shown a modi-
fication in the manner of securing the sec-
tions 12 and 13 to the plate 10, which con-
sists in employing a single rivet 19 for each
50 of said sections instead of a pair of rivets
for each section as shown in Figs. 1 and 2
and as above explained. In this modifica-
tion, the construction of the parts in practi-
cally the same as that shown in Fig. 2 ex-
55 cept that the rear portions of the sections
12 and 13 are slightly elongated as at 20 at
about the middle of their rear edges. This
construction will permit of slight lateral
movement of the sections which in some in-
60 stances may be advantageous.

By fastening the sections with hollow
rivets, it is evident that they can be easily
removed from the member 10 by crushing said
rivets inwardly when the sections may be
65 replaced by others of slightly different con-

formation. While I have shown two sec-
tions used in connection with the device, yet
I desire it to be understood that one or more
of the same may be employed without de-
parting from the spirit of the invention. 70

Having thus fully described my invention,
what I claim as new and desire to secure by
Letters Patent is:

1. A device of the character described,
consisting of an elongated supporting mem-
ber adapted to fit and be worn within a shoe,
a plantar muscle supporting plate secured
near its front and rear ends to said mem-
ber near its inner edge, said plate being of
sufficient length to extend forwardly from 75
the anterior portion of the heel to a point
located about one inch under the long or
metatarsal bones of the foot, said plate hav-
ing its rear portion downwardly and trans-
versely arched, and an upwardly curved sec-
tion transversely mounted on said member 80
above and extended forwardly of the front
portion of said plate.

2. A device of the character described,
consisting of an elongated flexible support-
ing member adapted to fit and be worn with-
in a shoe, a plantar muscle supporting plate
secured near its front and rear ends to said 90
member near its inner edge, said plate being
of sufficient length to extend forwardly from
the anterior portion of the heel to a point
located about one inch under the long or
metatarsal bones of the foot, said plate hav-
ing its rear portion downwardly and trans-
versely arched and its front portion up-
wardly and transversely arched, and a plu-
rality of upwardly curved sections trans-
versely mounted on said member above and
extended forwardly of the front portion of
said plate, said sections overlapping one an-
other. 100

3. A device of the character described,
consisting of an elongated flexible support-
ing member adapted to fit and be worn
within a shoe, a longitudinally arched 110
plantar muscle supporting plate secured
near its front and rear ends near its inner
edge to said member near the inner edge
thereof, said plate having its rear portion
downwardly and transversely arched and its
front portion upwardly and transversely
arched, and an upwardly curved section
transversely mounted on said member above
and extended forwardly of the front portion
of said plate. 115

4. A device of the character described,
consisting of an elongated flexible support-
ing member adapted to fit and be worn with-
in a shoe, a longitudinally arched plantar
muscle supporting plate secured near its
front and rear ends near its inner edge to 125
said member near the inner edge thereof,
said plate being of sufficient length to ex-
tend forwardly from the anterior portion
of the heel to a point located about one inch 130

- under the long or metatarsal bones of the foot and having its rear portion downwardly and transversely arched and its front portion upwardly and transversely 5 arched, and a plurality of upwardly curved sections transversely mounted on said member above and extended forwardly of the front portion of said plate, said sections overlapping one another.
- 10 5. A device of the character described, consisting of an elongated flexible supporting member adapted to fit and be worn within a shoe, and having at its inner edge an upturned longitudinally extended flange,
- a longitudinally arched plantar muscle supporting plate having at its inner edge an upturned longitudinally arched flange to underlie the flange of said member, said plate being secured near its front and rear ends near its inner edge to said member near 20 the inner edge thereof, said plate having its rear portion downwardly and transversely arched and its front portion upwardly and transversely arched, and an upwardly dished section transversely mounted on said 25 member above and extended forwardly of the front portion of said plate.

LEE W. V. WILMS.
